UNITED STATES PATENT OFFICE.

CHAUNCEY I. SPAYD, OF KANSAS CITY, MISSOURI.

IRONING-BOARD.

1,348,064.

Specification of Letters Patent. Patented July 27, 1920.

Application filed October 1, 1919. Serial No. 837,747.

To all whom it may concern:

Be it known that I, CHAUNCEY I. SPAYD, a citizen of the United States, residing at Kansas City, in the county of Jackson and 5 State of Missouri, have invented a certain new and useful Improvement in Ironing-Boards, of which the following is a specification.

My invention relates to improvements in 10 ironing boards. It relates to an ironing board adapted to be supported by a casing having drawers, such as a wardrobe trunk.

The object of my invention is to provide 15 an ironing board adapted for travelers' use and arranged to be supported in the operative position by attachment to a trunk in which the board may be stored when not in use.

A further object of my invention is to 20 provide a device of the kind described in which a locking bar, which is ordinarily used to lock the drawers closed, may be employed, when not so used, to support the ironing board in the operative position.

25 The novel features of my invention are hereinafter fully described and claimed.

In the accompanying drawing, which 30 illustrates the preferred embodiment of my invention,

Figure 1 is a perspective view of a wardrobe trunk provided with my improvement, the ironing board being shown, in solid lines, in the operative position, and in dotted lines stored in the trunk.

35 Fig. 2 is a vertical sectional view showing a portion of the trunk and the ironing board in the operative position.

Fig. 3 is a perspective view of the ironing board.

40 Fig. 4 is an enlarged vertical sectional view of a portion of the trunk, showing the locking bar in the locked position.

Similar reference characters designate 45 similar parts in the different views.

1 designates a trunk casing of the ordinary wardrobe type having pull-out drawers 2 and provided with a brace for holding the drawers closed comprising, preferably, two members 3 and 4, hinged together by a 50 horizontal pintle 5. The casing 1 is provided on its lower end and inner side with a socket plate 6, Fig. 1, adapted to receive the lower end of the member 3.

The member 4 on its inner side and ad- 55 jacent to its upper end is provided with a

lock 7 having a sliding bolt 8 which is adapted to releasably enter a recess 9 in the upper end and forward side of the casing 1, so as to releasably hold the drawers 2 in the closed position. 60

The above described parts are such as are commonly employed in wardrobe trunks.

10 designates an ironing board of the ordinary form which is provided at its rear end with one or more hooks 11 adapted to engage releasably with the rear edge of a transverse bar 12 attached at its ends to opposite sides respectively of the casing 1. The bar 12 is located just above and spaced apart from one of the drawers 2, upon which 70 the hooks 11 are adapted to rest when engaged with the bar 12, as shown in Fig. 2.

The under side of the ironing board 10 has attached to it a U-shaped plate 13 in which is adapted to enter the upper end of 75 the member 4, Fig. 2, for the purpose of supporting the ironing board 10 in the horizontal operative position.

The trunk is provided with the usual hinged top 14, within which the ironing 80 board 10, when not in use, may be stored, as shown in dotted lines in Fig. 1.

In the operation of my invention, the hooks 11 are inserted between the bar 12 and the drawer 2 next below, being supported 85 by said drawer and engaging the rear edge of the bar 12, as shown in Figs. 1 and 2. The member 4 is then swung outwardly and has its outer end inserted between the board 10 and the plate 13, thus holding the ironing 90 board in the horizontal operative position.

I do not limit my invention to the structure shown and described, as modifications, within the scope of the appended claims, may be made without departing from the 95 spirit of my invention.

What I claim is:—

1. In a device of the kind described, a casing provided with one or more drawers, an ironing board having means for attaching to the casing, and a brace having means for attachment to the casing so as to lock the drawers closed, and arranged, when in the unlocked position, to engage and support the ironing board in a horizontal position. 100

2. In a device of the kind described, a casing having one or more drawers, an ironing board having means for attachment to the casing, and a folding brace having means for attachment to the casing so as to lock the 110

drawers closed, and arranged to engage and support the ironing board in a horizontal position.

3. In a device of the kind described, a casing having one or more drawers, an ironing board having means for attachment to the casing, and a brace comprising two members hinged together and provided with means for attachment to the casing so as to lock the drawers closed, and arranged to have one of its members swung to the position in which it will engage and support the ironing board in a horizontal position.

4. In a device of the kind described, a casing having one or more drawers and a transverse bar, an ironing board having one or more hooks for engaging said bar, and a brace having means for attachment to the casing so as to hold the drawers closed and arranged to engage and support the ironing board in a horizontal position.

5. In a device of the kind described, a casing having one or more drawers and a transverse bar above one of the drawers, an ironing board adapted to be supported on the last named drawer and having one or more hooks for engaging said bar, and a brace having means for attachment to the casing so as to hold the drawers closed and

arranged to engage and support the ironing board in a horizontal position.

6. In a device of the kind described, a casing having one or more drawers and a transverse bar above one of the drawers, an ironing board adapted to be supported on the last named drawer and having one or more hooks for engaging said bar, and a folding brace arranged to engage the casing and hold the drawers closed, and arranged to be swung to a position in which it will engage and support the ironing board in a horizontal position.

7. In a device of the kind described, a casing having one or more drawers and a transverse bar above one of the drawers, an ironing board adapted to be supported on the last named drawer and having one or more hooks for engaging said bar, and a brace comprising two members hinged together and having means for attachment to the casing in a position for holding the drawers closed, one of said members being adapted to be swung to a position in which it will engage and support the ironing board in a horizontal position.

In testimony whereof I have signed my name to this specification.

CHAUNCEY I. SPAYD.
